Primary Examiner — Joseph Kukella*Assistant Examiner* — Heather Ann Laaveg Wencl(74) *Attorney, Agent, or Firm* — Wolf, Greenfield & Sacks, P.C.(57) **CLAIM**

The ornamental design for doorbell mount, as shown and described.

DESCRIPTION

FIG. 1 shows a lower front right perspective view of a mount portion of the doorbell mount;

FIG. 2 shows an upper rear right perspective view thereof;

FIG. 3 shows a front view thereof;

FIG. 4 shows a rear view thereof;

FIG. 5 shows a left side view thereof;

FIG. 6 shows a right side view thereof;

FIG. 7 shows a top view thereof; and,

FIG. 8 shows a bottom view thereof.

In the drawings, the broken lines depict environmental subject matter that forms no part of the claimed design.
